UNITED STATES PATENT OFFICE.

JACQUES MAYER, OF BERLIN, GERMANY, ASSIGNOR TO MERGENTHALER LINOTYPE COMPANY, A CORPORATION OF NEW YORK.

APPARATUS FOR AUTOMATICALLY OPERATING TYPOGRAPHICAL AND OTHER SELECTIVELY-OPERATED MACHINES.

1,306,919.

Specification of Letters Patent. Patented June 17, 1919.

Application filed May 18, 1916. Serial No. 98,468.

To all whom it may concern:

Be it known that I, JACQUES MAYER, a citizen of the United States of America, residing at Kurfurstendamm 181, Berlin, Germany, have invented new and useful Improvements in Apparatus for Automatically Operating Typographical and other Selectively-Operated Machines, of which the following is a specification.

10 This invention relates to apparatus for automatically operating typographical and other selectively operated machines. It is especially applicable for use in connection with, and is hereinafter for convenience described as applied to, typographical composing machines such as those known commercially under the trade mark "Linotype", wherein the release of matrices, type-dies or the like from the magazine in which they 15 are stored, is normally effected by mechanism controlled from a manually operated keyboard. It has heretofore been proposed to automatically operate such machines by means of mechanically, electrically or pneumatically actuated devices, acting either directly on the keys or on other organs connected with the matrix-releasing devices, and controlled by means of a paper strip having perforations corresponding to the 20 keys to be struck or matrices to be released. The operation of such devices has usually involved the provision of either a great number of electric or pneumatic conductors which are difficult to inspect, or direct and 25 complicated lever connections, between the paper strip and the keys or releasing devices to be actuated.

According to the present invention, the just-named disadvantages are eliminated, 40 and the operation of a large number of keys or releasing devices through the medium of a small number of pneumatic conductors is rendered possible by the use of a special controlling device interposed between the 45 perforated strip and the striking devices, in conjunction with an improved system of perforations on the strip according to which two such perforations are employed for the actuation of each striking device. In addition to providing these improved means for actuating the matrix-releasing devices, the 50 present invention also includes mechanism, under the control of the perforated strip, which elevates the assembler, wherein the

matrices are composed in line, in order to 55 permit the removal of a completed line therefrom, and returns it to its line-receiving position, and means for preventing the automatic operation of the matrix-releasing devices in the event of the assembler failing 60 to return to the last-mentioned position.

The invention will now be described with reference to the accompanying drawings, which illustrate a constructional form thereof as applied to a matrix-composing machine, and in which:—

Figure 1 is a side elevation of the apparatus, partly in section, and showing diagrammatically the relevant parts of the matrix-composing machine;

Fig. 2 an elevation as seen from the left of Fig. 1, partly in section and with certain parts omitted;

Fig. 3 a sectional detail of the controlling device, on an enlarged scale, taken on the 75 line 3—3 of Fig. 4;

Fig. 4 a front view of the controlling device with the conductors removed, and partly in section;

Fig. 5 a sectional plan taken on the line 80 5—5 of Fig. 4; and

Fig. 6 a detail view of the striking devices.

Referring to Fig. 1, part of the frame of the matrix-composing machine adjacent to the keyboard thereof is indicated at 1, 2 85 being a part of a key-lever, which on the depression of the key, raises the respective key rod 3, thereby releasing the so-called cam-yoke to bring the cam 4 into contact with the constantly rotating roller 5 which, 90 acting through the cam-yoke, raises the escapement reed 6 whereby the escapement is actuated and a matrix released from the respective channel of the magazine. All the escapement-actuating devices just referred 95 to are of well-known construction, and operate in the known manner. As a convenient means of employing the automatic actuating devices hereinafter described, so as to render them available without the necessity of effecting any special connection or disconnection when changing from manual to automatic operation of the machine or vice versa, each key rod 3, in the constructional form 100 illustrated, is provided with a rearwardly-extending portion or finger 7, beneath which the pneumatic strikers 8 are arranged so that when the latter are operated they will 105

raise the key rods, the matrix-releasing devices being thereby actuated in the same manner as when the key rods are raised by the manual depression of the keys.

- 5 In order to provide sufficient room to accommodate the strikers 8, they are arranged in two rows, those in one row being in staggered relationship to those in the other row, and the fingers 7 may conveniently be
 10 made long enough to be acted upon by the strikers in the outer row. Each of the strikers 8, as shown in detail in Fig. 6, constitutes the upper end of a piston working in a cylinder 9, which cylinder is connected
 15 by a conductor or pipe 10 with the special controlling or distributing device provided according to the present invention.

The construction of the controlling device is best illustrated in Figs. 3, 4 and 5 of the drawings. Broadly speaking, it consists of a frame 13 having a number of pneumatic channels and ports, connected, in a manner hereinafter more particularly described, on the one hand with a pneumatic pressure supply controlled by a perforated strip, and on the other with the above-described cylinders 9.

- The above mentioned conductors 10 connecting the cylinders 9 with the controlling device, communicate with the latter through
 30 openings or ports 11 in front plates 12 secured to the frame 13 by screws 14. Three such front plates 12 are shown in the drawings, but any other suitable number of such
 35 plates of convenient size could be substituted therefor if desired. The ports 11 are arranged in rows or groups, vertically as well as horizontally, and in the arrangement illustrated there are six horizontal rows or
 40 groups and seventeen vertical rows or groups, comprising in all one hundred and two ports. Behind each horizontal row or group of ports 11, there is a control bar or valve 15, which is capable of sliding in a
 45 groove in the frame 13. Each of the six control bars 15 is provided with openings corresponding in number and relative position with the ports 11 in the respective horizontal row, by means of which, accord-
 50 ing to the position of the bar 15, connection is established or prevented between the ports 11 and corresponding ports 16 in the frame 13. All the ports 16 in one vertical row or group communicate with a common vertical
 55 channel or chamber 17 in the frame 13, and each of the seventeen vertical channels 17 is connected by a conductor 18 with a common
 60 tracker bar 19 over which the perforated strip 20 is traversed, as shown in Fig. 1.
 65 Due to their connection to the ports 11, the conductors 10 may be regarded as divided into similar groups; that is to say, the conductors connected to the ports of the vertical rows constitute a plurality of groups, each of which is supplied with the

fluid pressure from a single conductor 18 through the medium of the common connecting or distributing channel 16, while in another sense those conductors 10 connected to the ports of the horizontal rows constitute a plurality of groups in each of which one conductor is connected to each of the channels 16.

Each of the control bars 15 is fast at one end to a piston 21 working in a cylinder 22 formed in a block 23 secured to the frame 13, and is normally held in its left-most position, wherein its holes are out of register with the ports 11 and 16, as shown in connection with the top or first, third, fourth, fifth and bottom bars in Figs. 3 and 4, by a spring 24 acting between the piston and the respective end of the cylinder 22. The movement of a bar to the right, to the position in which the bar represented in Fig. 5 is shown, with the holes in the bar in register with the ports 11 and 16, is effected by pneumatic pressure, supplied through a conductor 25 leading from a port in the respective cylinder 22 to the tracker bar 19, which moves the piston 21 to the right against the action of the spring 24. The latter will, of course, restore the bar to its normal left-most position as soon as the pneumatic pressure is released.

The admission of pressure to the conductors 18, 25, is controlled by the perforated strip 20, which is stored on a spool 26, and in known manner carried therefrom over the tracker bar 19, and wound, with an intermittent motion derived by any suitable means from the constantly rotating shaft 27, on to a second spool 28, each intermittent forward movement of the strip bringing a combination of perforations corresponding to the matrix-releasing device to be actuated into register with the ports on the tracker bar communicating with the respective conductors 18, 25. Compressed air is supplied, from any suitable source, through a valve 29 to a pressure chamber 30 which communicates with a mouthpiece 31, so that when the mouthpiece is, as next to be described, moved down into air-tight contact with the perforated strip, compressed air is admitted therethrough to the particular conductors determined by the strip perforations then lying over the tracker bar ports, there being two such perforations for each matrix releasing device, one to admit pressure to a conductor 18, and the other to admit pressure to a conductor 25.

The movement of the pressure chamber 30 to bring the mouthpiece 31 down on to the paper strip, is accomplished by a cam 33 fast to the before-mentioned constantly rotating shaft 27, which is driven by a belt 34 from a pulley 74 on the main shaft 35 as will be hereinafter explained. A roller 36 on a lever 37 fulcrumed at 38 on the frame 130

39, is held in contact with the cam 33 by a spring 40. The lever 37 is connected to the pressure chamber 30 through a link 41 and a lever 42 pivoted to an upstanding arm 43 which is itself pivoted on the said frame at 44, and is integral with an arm rigid upon the pressure chamber 30. A rod 122 screwed or otherwise rigidly secured to a lug 46 on the pressure chamber 30, passes loosely through the lever 42 and terminates on the upper side of the latter in a head 32. This rod 122 is encircled by a spring 45 between the lever 42 and a nut or collar on the rod. The lever 42 has adjustably secured thereon a set-screw 47, adapted to bear on and open the valve 29. When the lever 37 is depressed by the cam 33, against the influence of the spring 40, the lever 42 is depressed so as, through the spring 45, to resiliently hold the mouthpiece 31 in airtight contact with the perforated strip 20 and at the same time, through the set-screw 47, open the valve 29 and thereby admit compressed air into the said mouthpiece. As soon as the rotation of the cam 33 has caused the lesser radius thereof to be presented to the roller 36, the spring 40 raises the lever 37 which through the link 41, raises the lever 42 together with the set-screw 47, thus allowing the valve 29 to close (under the action of a spring or the pressure of the air). The continued upward movement of the lever 42 brings the latter into contact with the head 32, after which this lever together with the pressure chamber 30 and upstanding arm 43, rock as a complete entity about the pivot 44 so as to raise the mouthpiece 31 out of contact with the perforated strip 20.

The manner in which the strikers 8 are operated will now be understood. Immediately after the strip 20 has received a forward movement the cam 33 acts on the lever 37 and brings the mouthpiece 31 down into close contact with the strip 20 at the same time causing the opening of the valve 29 and the admission of compressed air into the mouthpiece 31 whence it passes through the two strip-perforations then in operative position, into the respective conductors 18 and 25. The pressure in the conductor 25 moves the respective piston 21 to the right (as shown in Fig. 5), and by the consequent movement of the appropriate bar 15, establishes a connection between all the ports 16 and 11 in one horizontal row. The pressure in the conductor 18 is led into the respective channel 17, which, as above described, communicates with all the ports 16 in one vertical row. As, however, only one bar 15 has been moved to the right, there is at this time only one port 16 through which the pressure can pass into a conductor 10 in order to act on the respective striker 8 and effect the release of a matrix as previously described. It will be seen that by

these means, in the example illustrated, 102 matrix-releasing devices can be operated by 23 conductors connected with the tracker bar.

As thus far described, the apparatus deals only with the release of matrices from their magazines. In the machine to which the invention is herein shown as applied, the matrices, when so released, are assembled in line in an assembler 48, and when a complete line has been composed, the assembler is raised so that the line may be removed therefrom by a line carriage 49, and thereafter lowered again into position to receive the next line to be composed. The raising and lowering of the assembler is effected automatically according to the present invention, under the control of the perforated strip, by the mechanism illustrated in Figs. 1 and 2 of the drawings and now to be described.

A special pair of perforations, adapted to admit pressure to a conductor 50, are arranged on the strip 20 to follow the series of perforations representing the matrices and spacers in each complete line, so that the movement of the strip following the release of the last matrix of the line will bring the said perforations into position to establish connection between the tracker bar 19 and that conductor, and on the next ensuing descent of the mouthpiece 31 and opening of the valve 29, compressed air will be conveyed beneath a piston 51, which will be thereby raised. The piston acts on the horizontal arm of a bell-crank lever 52, fulcrumed on a lug 53 extending from one of the standards supporting the main shaft 35 previously referred to. The said shaft 35 is hollow, and has mounted within it a rod 54, an extension of which is embraced by the forked upstanding arm of the bell-crank lever 52 which, acting between two collars 55, 56 on the rod, is capable of moving the latter axially relatively to the shaft 35.

The main driving pulley 57 is freely mounted on the main shaft 35, and is constantly driven by a belt 58 from the driving motor of the machine; it is provided with clutch-teeth 59 adapted to engage a clutch 60 which is secured to the rod 54 by a pin 61^a passing through horizontal slots in the said shaft, so that axial movement of the rod 54 will be transmitted to the clutch 60 and result in the rotation or stoppage of the shaft 35 by the connection of that clutch with or its disconnection from the pulley 57.

When the bell-crank lever 52 is actuated by the piston 51, as above-mentioned, the rod 54 will be moved to the left, into the position in which it is shown in Fig. 2, the clutch 60 will be thereby thrown into gear with the clutch-teeth 59 on the pulley 57, and the shaft 35 will be rotated until the clutch is again disconnected.

Fast on the shaft 35 is a spur pinion 61, meshing with a gear wheel 62 secured on a shaft 63, which also has fast on it a cam or eccentric 64 engaging a roller 65 of a lever 66, which lever, acting through a link 67, effects the raising of the assembler 48. One half a rotation of the cam 64 raises the assembler to its line-delivering position, and during the next half-revolution the assembler 10 is allowed to return to its line-receiving position. Consequently, only one complete rotation of the shaft 63 is required for the desired movement of the assembler, and for the purpose of stopping the rotation of the 15 shafts 35 and 63 on the completion of one revolution of the latter, there are provided a collar 68 loosely encircling the shaft 35 and secured to the rod 54 by a pin 69 passing through longitudinal slots in that shaft; and 20 a lever 70, fast to a shaft 71 rocking in bearings mounted on the base plate of the apparatus, and extending into the path of a projection 72 fast to the respective side of the gear wheel 62. When the rod 54 is 25 moved to the left (Fig. 2) to throw in the clutch 60, it carries with it the collar 68, which is brought into contact with a nose 73 on the lever 70. The projection 72 is so positioned on the gear wheel 62 that, on the 30 completion of one rotation of the latter, it comes into contact with the upper end of the lever 70, forcing that end toward the right, and through the nose 73 and collar 68, moves the rod 54 to the right, thus disconnecting 35 the clutch 60 from the pulley 57, and stopping the rotation of the shaft 35.

The before-mentioned pulley 74 is loose on the shaft 35, and is engaged by clutch teeth 75 with the pulley 57, with which it is normally 40 held in contact by a spring 76 bearing between it and a collar 77 fast on the shaft 35. It will thus be seen that the rotation of the pulley 74, and consequently the movement of the strip 20, is not interfered with 45 during the raising and lowering of the assembler, but, as there will be no perforations on the portion of the strip 20 which passes over the tracker bar 19 during that operation, no matrices will be released. The unperforated portion of the strip, however, will only extend over as much of the strip as will be traversed over the tracker bar during the period occupied by one rotation of the gear wheel 62. Consequently, if the assembler 50 should for any reason fail to return to its line-receiving position during that period, composition would be automatically resumed, but would be ineffective owing to the inability of the assembler to receive the released matrices. Any such improper release 55 of matrices is prevented, in the event of the assembler failing to descend after having delivered a line by the following devices.

A plate 78 is mounted on the shaft 63 by a 60 slotted bearing 79 and secured to the cam 64

by screws 80 passing through slots in the plate, to enable it to rotate with the said cam, with a capacity for moving radially relatively to the axis of rotation. One end of the plate 78 is in contact with a lever 81 70 pivoted on the cam 64 at 82 and constantly urged against that end of the plate by a blade spring 83 fast to the cam 64, tending to move the plate radially and protrude its outer edge beyond the periphery of the cam 75 64. Pivoted on a shaft 84 mounted in brackets 85 on the base plate of the apparatus, is a bell-crank lever 86, 87, the upstanding arm 86 of which is provided with a T-head 88 extending, in one direction, toward the cam 80 64, the other arm 87 being normally held, by a spring 89, in the path of a lever 90 in such a way as to prevent the latter moving to the right (Fig. 2), about the axis of a rocking shaft 91 to which it is fast, under the action 85 of a spring 92. The connection of the last-mentioned spring with the lever 90 is not shown in the drawings, as the respective part of the said spring is represented in Fig. 2 as broken away for the sake of clearness. 90 The lever 81 is provided with a lateral projection 93 which, under certain circumstances, is capable of engaging with the head 88 on the lever arm 86. In the position in which the parts are shown in Fig. 1, 95 the assembler is in its lowest position, the roller 65 on the lever 66, serving to keep the plate 78 depressed against the action of the spring 83, and the lever 81 in such a position that on the subsequent rotation of the cam 100 64, its projection 93 will clear the head 88. This relative position of the plate 78 will be maintained until the rotation of the cam 64 permits the spring 83 to act and, through the lever 81, protrude the plate 78 beyond 105 the periphery of the said cam; but by that time the projection 93 will have passed the head 88 without coming into contact with it. If the assembler descends normally, just before it again reaches its lowest position, the 110 roller 65 will contact with the approaching edge of the plate 78 and depress it, thereby moving the lever 81 again into the position shown in Fig. 1, immediately after which the projection 72 on the gear wheel 62 will 115 act, as above described, to stop the rotation of the shafts 35 and 63. If, however, the assembler should fail to descend, the plate 78 will be maintained in its protruded position, and, before the projection 72 can act, 120 the projection 93 on the lever 81 will come into contact with the head 88 moving the latter toward the right in Fig. 1, and raising the lever arm 87 clear of the lever 90, thus permitting the latter to be moved by 125 the spring 92. As shown in Fig. 2, shaft 91 has fast on it an upstanding arm 90^a which is connected by a link 94 and screw-and-slot connection 95 with the lever 70, by which means the last-mentioned movement of the 130

lever 90 will move the lever 70 to the right, which in turn, through the projection 73 and collar 68, will move the rod 54 far enough to the right, not only to disengage the clutch 60 from the pulley 57 but also through the said clutch to move the pulley 74 to the right, against the action of the spring 76, out of engagement with the pulley 57, thus stopping the operation of the strip 20 as well as the shafts 35 and 63. The obstruction to the proper descent of the assembler can then be removed, and the levers reset ready for the operation of the machine to be resumed. For this latter purpose, a hand lever 96 (seen only in Fig. 1) is provided fast on the shaft 91, by which that shaft can be rocked in order to return the lever 90 against the action of the spring 92. Before this return movement of the lever 90 takes place, the lever 86, 87 will have been returned to its normal position under the influence of its spring 89, by the readjustment of the plate 78 and the consequent disengagement of the projection 93 from the head 88. The lever arm 87 will therefore stand in the path of the returning lever 90, and is arranged to act as a latch, lifting to allow the lever 90 to pass, but immediately thereafter locking the said lever against the action of the spring 92. The slot-and-screw connection 95 between the link 94 and lever 70, permits the latter to rock when acted upon by the projection 72 or collar 68 without affecting the lever 90 and the co-operating parts.

To insure that the cam 64 shall come to rest in the correct position when the clutch 60 is thrown out, a lever 97 is mounted on the before-mentioned shaft 84, one arm of which is provided with a roller 98 kept constantly in contact with the periphery of the cam 64 by a spring 99 acting on the opposite arm of the lever. The cam 64 is provided with a notch 100 which, in conjunction with the roller 98 engaging therewith when the cam reaches its position of rest, acts as a yielding stop to assist the weight of the parts in preventing overrunning of the shaft 63.

It may sometimes happen that, through the presence of an improperly placed matrix, or some other obstruction, the assembler cannot be raised to deliver the line. In this event, also, a complete stoppage of the apparatus obviously becomes necessary. In order to permit of this stoppage being effected automatically, the link 67 which connects the assembler 48 with the lever 66 is in resilient connection with the latter, through a bent link 101, which is pivoted at one end to the free end of the said lever, and has a boss 102 on its opposite end encircling the lower end of the link 67, the lift of the lever 66 being transmitted to that link through a spring 103 arranged between the boss 102

and a collar 104 on the link. If the assembler 48 is prevented from leaving its line-receiving position, or is arrested before reaching its line-delivering position, the lever 66 is by these means permitted to continue its upward movement for a short distance, while the link 67 remains at rest. A bell-crank lever 105 is pivoted at the free end of the lever 66, one arm of which extends beneath the end of the link 67 protruding through the boss 102, the other arm being connected by a link 106 to one arm of a bent lever 107 pivoted on a stud-shaft 108, on which is also fulcrumed the lever 66. The second arm of the bent lever 107 is connected by a link 109 to an arm 110 operatively fast to the lever 86, 87. When the lever 66 moves upward while the link 67 remains at rest (which movement occurs in the event of the rise of the assembler 48 being obstructed as above-mentioned), the lower end of the link 67 causes a movement of the bell-crank lever 105 about its pivot, which movement is transmitted, by the link and lever connections just described, to the lever arm 87, whereby, in the manner previously described, the apparatus is stopped by the action of the spring 92 on the levers 90 and 70.

The present invention further provides means for stopping the automatic operation of the assembler elevating and matrix-releasing devices in the event of the line carriage 49 not being in a proper position to receive the line from the assembler 48. These means consist of a bell-crank lever 111 pivoted to one side of the gear wheel 62; a pin 112 pivoted to one arm of the lever 111 and normally protruding through an opening in the gear wheel 62, and a rod 113 depending from one arm of a bell-crank lever 114 the upstanding arm of which is held, against the action of gravity, by the line carriage 49, when this latter is in its line-receiving position. The normal position of the pin 112 is such that it will, as the gear wheel 62 rotates come into contact with the head 88 on the lever arm 86, and thus effect the stoppage of the apparatus in the manner which will now be well understood. The lower end of the rod 113 has a projection which, when the line carriage is in its line-receiving position, is held by the action of the bell-crank lever 114, in the path of the free end of the bell-crank lever 111, and that end of the said lever will be raised by riding over the said projection, thus withdrawing the pin 112 and preventing it contacting with the head 88. If the line carriage is not in its correct position, the rod 113 will remain in a position in which its projection is below the path of the bell-crank lever 111, the pin 112 will not be withdrawn and will act, as above-mentioned, to stop the apparatus.

In order to enable the apparatus to be stopped by hand whenever it may be desired to do so, a shaft 115 carrying a cam 116 and provided with a handle 117, is mounted in 5 bearings formed in a bracket 118 attached to the base of the frame 13. A rod 119, guided at its upper end in the bracket 118, and at its lower end in a fixed bracket 120, is held in constant contact with the cam 116 by a 10 spring 121, its lower end being in a position to act, when depressed, on the substantially horizontal arm of the bell-crank lever 52; these parts are shown in their inoperative position in Fig. 2. If the handle 117 is 15 turned 90° from the position there shown, the cam 116 will depress the rod 119, which, acting through the lever arm 52, will force the rod 54 to the right far enough to disengage the clutch 60 from the pulley 57, and 20 to also effect the disengagement of the pulley 74. When the handle 117 is turned back, the reengagement of the pulley 74 with the pulley 57 is automatically effected by the 25 spring 76, and the composing mechanism is re-started.

It will be readily understood that, although the mechanism is herein described as applied to the operation of matrix-releasing devices and the assembler in a typographical 30 composing machine, it may equally well be applied to matrix-releasing devices and a periodically operated organ other than the assembler, and to other machines, for example, to typewriters, in which case the striking devices could be arranged to operate on the keys or key levers, and what is herein termed the assembler elevating mechanism could be applied to the purpose of operating 35 the paper carriage. Further, the substitution of a vacuum for compressed air as the operating medium would not present any difficulty. It is, therefore, to be understood that any such application or substitution falls within the scope of the invention.

Having described my invention, I declare that what I claim and desire to secure by Letters Patent is:—

1. In a machine of the class described, the combination of a series of strikers, a perforated strip, a fluid pressure apparatus controlled by said strip for actuating the strikers, the said apparatus including a set of conductors, a second set of conductors of a number different from that in the first set 50 and adapted selectively to communicate therewith, and a device interposed between the two sets and acting under the control of the strip to govern the connection of the desired conductors.

2. In a machine of the class described, the combination of a series of strikers, a perforated strip, and fluid pressure apparatus controlled by said strip for actuating the strikers, the said apparatus including a controlling or distributing device, a set of con-

ductors leading from the perforated strip to said device, and a second set of conductors of a number different from that in the first set and leading from said device to the strikers, the said device acting under the control of 70 the strip selectively to establish operative connection between the conductors of the different sets.

3. In a machine of the class described, the combination of a series of strikers, a perforated strip, a fluid pressure apparatus controlled by said strip for actuating the strikers, the said apparatus including a controlling device formed with channels, and two sets of conductors, one under control of 75 the perforated strip and leading to said channels, and the other of a number different from that of the first set and located between said channels and the respective strikers, the said controlling device acting 80 under the control of the strip to establish selective connection between its respective channels and the conductors of the two sets.

4. In apparatus for automatically operating typographical and other selectively operated machines, the combination with strikers and a perforated strip adapted to control the actuation thereof, of a controlling device, conductors under the control of the perforated strip, channels in the controlling 90 device each connected with one of the said conductors, groups of conductors between the controlling device and respective strikers, each such group consisting of one conductor adapted to connect with each channel, 95 and means adapted to simultaneously connect and simultaneously disconnect all the conductors of any one group with and from the channels.

5. In apparatus for automatically operating typographical and other selectively operated machines, the combination with strikers and a perforated strip adapted to control the actuation thereof, of a controlling device, conductors under the control of the perforated strip, channels in the controlling device each connected with one of the said conductors, a group of conductors between each channel and respective strikers, and control bars adapted to be moved to establish and 110 disestablish connection between any conductor and the respective channel.

6. In apparatus for automatically operating typographical and other selectively operated machines, the combination with strikers and a perforated strip adapted to control the actuation thereof, of a controlling device, conductors under the control of the perforated strip, channels in the controlling device each connected with one of the said conductors, groups of conductors between the controlling device and respective strikers, each such group consisting of one conductor adapted to connect with each channel, and a control bar appropriate to each such group 115 120 125 130

adapted to be moved to simultaneously connect and simultaneously disconnect all the conductors of the respective group with and from the channels.

- 5 7. In apparatus for automatically operating typographical and other selectively operated machines, the combination of strikers, a perforated strip having a pair of perforations to control the actuation of each striker,
 10 a controlling device interposed between the said strip and strikers, a group of conductors controlled by one perforation of each pair, channels in the controlling device each connected with one conductor of the said
 15 group, a group of conductors between each channel and respective strikers, a group of conductors controlled by the other perforation of each pair, control bars in the controlling device each connected with one conductor
 20 of the last-mentioned group and adapted to be moved by the energizing of the respective conductor to establish connection between a channel and a conductor leading from that channel to a selected striker, and
 25 means adapted to return each control bar to and normally retain it in a position in which the respective channel and conductor are disconnected.

8. In apparatus for automatically operating typographical and other selectively operated machines, the combination of strikers, a perforated strip having a pair of perforations to control the actuation of each striker, a controlling device interposed between the said strip and strikers, a group of conductors controlled by one perforation of each pair, channels in the controlling device each connected with one conductor of the said group, groups of conductors between
 35 the controlling device and respective strikers, each such group consisting of one conductor adapted to connect with each channel, a group of conductors controlled by the other perforation of each pair, control bars
 40 in the controlling device each connected with one conductor of the last-mentioned group and adapted to be moved by the energizing of the respective conductor to establish connection between all the channels and all the
 45 conductors of one group between said channels and respective strikers, and means adapted to return each control bar to and normally retain it in a position in which the channels and the respective group of
 50 conductors are disconnected.

9. In apparatus for automatically operating typographical and other selectively operated machines, the combination with strikers and a perforated strip adapted to control the actuation thereof, of a tracker bar over which the strip is traversed, a chamber through which power to actuate the strikers is transmitted, means adapted to move the chamber into and out of contact
 60 with the strip, and means adapted to auto-

matically connect and disconnect the chamber with and from the power supply when the said chamber is moved respectively into and out of contact with the strip.

10. In a machine of the class described, 70 the combination of a series of strikers, a perforated strip, and fluid pressure apparatus controlled by said strip for actuating the strikers, the said apparatus including a controlling or distributing device interposed 75 between the perforated strip and the strikers and acting automatically to control the selection of the striker to be actuated, with a further striker to actuate a periodically operated part, and mechanism under the 80 control of the perforated strip to effect the actuating movement of said last mentioned striker.

11. In apparatus for automatically operating typographical and other selectively 85 operated machines, the combination with strikers and a perforated strip adapted to control the actuation thereof, of mechanism adapted to effect the normal movement of a periodically operated organ of the machine, 90 means under the control of the perforated strip adapted to start the said mechanism, and means adapted to stop the said mechanism on the completion of the normal movement of the said organ. 95

12. In apparatus for automatically operating typographical and other selectively operated machines, the combination with strikers and a driven perforated strip adapted to control the actuation thereof, of mechanism adapted to effect the normal movement of a periodically operated organ of the machine, means under the control of the perforated strip adapted to start the said mechanism, and means adapted to stop the said 105 mechanism and strip when the normal movement of the said organ is obstructed.

13. In apparatus for automatically operating typographical and other selectively operated machines, the combination with 110 strikers and a driven perforated strip adapted to control the actuation thereof, of mechanism adapted to effect the movement of a periodically operated organ of the machine which cooperates with another periodically 115 operated organ thereof when the latter is in a given position, means under the control of the perforated strip adapted to start the said mechanism and means adapted to stop the said mechanism and strip when the last-mentioned organ is not in the said position. 120

14. In apparatus for automatically operating typographical and other selectively operated machines, the combination with strikers and a perforated strip adapted to 125 control the actuation thereof, of a shaft, a constantly rotated pulley loose thereon, a clutch angularly fast to the shaft and adapted to be thrown into and out of operative connection with the pulley, a cam rotated 130

by the rotation of the shaft, a projection rotating with the cam, means under the control of the perforated strip adapted to throw in the clutch, and means operated by the

5 projection adapted to throw out the clutch at the end of a complete rotation of the cam.

15. In apparatus for automatically operating typographical and other selectively operated machines, the combination with strikers and a driven perforated strip adapted to

10 control the actuation thereof, of a shaft, a constantly rotated pulley loose thereon, a pulley adapted to operate the strip-driving mechanism also loose on the shaft, means adapted to maintain the two pulleys in driving connection, a clutch located between the two pulleys angularly fast to the

15 shaft and adapted to be thrown into and out of operative connection with the constantly rotated pulley and to be moved axially on the shaft far enough to disconnect the two pulleys, means under the control of the perforated strip adapted to throw in the clutch, a spring-controlled lever constantly tending to

20 throw out the clutch and disconnect the two pulleys, a latch normally preventing the operation of the lever, a cam rotated by the rotation of the shaft, a lever normally maintained in operative engagement with the

25 cam and means rotating with the cam adapted to effect the release of the spring-controlled lever when the cam operated lever is not in operative engagement with the cam during a portion of a rotation of the latter.

30 16. In an apparatus for automatically operating typographical and other selectively operated machines, the combination with strikers and a driven perforated strip adapted to control the actuation thereof, of a

35 shaft, a constantly rotated pulley loose thereon, a pulley adapted to operate the strip-driving mechanism also loose on the shaft, means adapted to maintain the two pulleys in driving connection, a clutch located between the two pulleys angularly fast to the shaft and adapted to be thrown into and out of operative connection with the constantly rotated pulley and to be moved axially on the shaft far enough to disconnect

40 the two pulleys, means under the control of the perforated strip adapted to throw in the clutch, a spring-controlled lever constantly tending to throw out the clutch and disconnect the two pulleys, a latch normally pre-

45 venting the operation of the lever, a cam rotated by the rotation of the shaft, a plate rotating with the cam and movable radially relatively thereto to protrude one of its edges beyond the periphery thereof, a spring-

50 pressed lever pivoted to the cam and constantly tending to so protrude the said edge, a lever normally maintained in operative engagement with the cam and adapted to de-

55 press the protruded edge of the plate and the 60 spring-pressed lever during a portion of

each rotation of the cam, and a projection on the spring-pressed lever adapted when it is not so depressed to effect the release of the said spring-controlled lever.

17. In apparatus for automatically operating typographical and other selectively operated machines, the combination with strikers and a driven perforated strip adapted to control the actuation thereof, of a shaft, a constantly rotated pulley loose thereon, a pulley adapted to operate the strip-driving mechanism also loose on the shaft, means adapted to maintain the two pulleys in driving connection, a clutch located between the two pulleys angularly fast to the shaft and adapted to be thrown into and out of operative connection with the constantly rotated pulley and to be moved axially on the shaft far enough to disconnect the two pulleys, means under the control of the perforated strip adapted to throw in the clutch, a spring-controlled lever constantly tending to throw out the clutch and disconnect the two pulleys, a latch normally preventing the operation of the lever, a cam rotated by the rotation of the shaft, a lever operated by the cam and adapted to effect the normal movement of a periodically operated organ of the machine, and means adapted to effect the release of the spring-controlled lever when the normal movement of the said organ is obstructed.

18. In apparatus for automatically operating typographical and other selectively operated machines, the combination with strikers and a driven perforated strip adapted to control the actuation thereof, of a shaft, a constantly rotated pulley loose thereon, a pulley adapted to operate the strip-driving mechanism also loose on the shaft, means adapted to maintain the two pulleys in driving connection, a clutch located between the two pulleys angularly fast to the shaft and adapted to be thrown into and out of operative connection with the constantly rotated pulley and to be moved axially on the shaft far enough to disconnect the two pulleys, means under the control of the perforated strip adapted to throw in the clutch, a spring-controlled lever constantly tending to throw out the clutch and disconnect the two pulleys, a latch normally preventing the operation of the lever, a cam rotated by the rotation of the shaft, a lever operated by the cam, a yielding connection between that lever and a periodically operated organ of the machine, and means actuated by relative movement between the said lever and organ when the connection yields and adapted to effect the release of the spring-controlled lever.

19. In apparatus for automatically operating typographical and other selectively operated machines, the combination with strikers and a driven perforated strip

adapted to control the actuation thereof, of a shaft, a constantly rotated pulley loose thereon, a pulley adapted to operate the strip-driving mechanism also loose on the shaft, means adapted to maintain the two pulleys in driving connection, a clutch located between the two pulleys angularly fast to the shaft and adapted to be thrown into and out of operative connection with the constantly rotated pulley and to be moved axially on the shaft far enough to disconnect the two pulleys, means under the control of the perforated strip adapted to throw in the clutch, a spring-controlled lever constantly tending to throw out the clutch and disconnect the two pulleys, a latch normally preventing the operation of the lever, a cam rotated by the rotation of the shaft, a lever operated by the cam and adapted to effect the normal movement of a periodically operated organ of the machine which coöperates with another periodically operated organ thereof when the latter is in a given position, a lever rotating with the cam and adapted to effect the release of the spring-controlled lever, a normally inoperative rod adapted to prevent the releasing action of the rotating lever, and means adapted to render the said rod operative when the last mentioned organ is in the said position.

20. In apparatus for automatically operating typographical and other selectively operated machines, the combination with strikers and a driven perforated strip adapted to control the actuation thereof, of mechanism adapted to effect the normal movement of a periodically operated organ of the machine, means under the control of the perforated strip adapted to start the said mechanism, and means controlled by the operator adapted to stop the said mechanism and strip.

21. In a machine of the class described, the combination of a series of strikers, a perforated strip, and a fluid pressure apparatus controlled by said strip for actuating the strikers, the said apparatus including a set of conductors, one connected to each striker, a second set of conductors of less number than that of the other set and coöperating with the strip, and means also controlled by the strip to establish communication between different selected conductors of the two sets.

22. In a machine of the class described, the combination of a series of strikers, a perforated strip, and a fluid pressure apparatus controlled by said strip for actuating the strikers, the said apparatus including a set of conductors connected to the respective strikers, a second set of conductors of less number than that of the other set and coöperating with the perforated strip, and a distributing device acting under the control of the perforated strip to establish com-

munication between a conductor of the second set with different selected conductors of the first set.

23. In a machine of the class described, the combination of a plurality of strikers, and a fluid pressure apparatus for actuating the strikers and including a plurality of conductors one for each striker, and a supply conductor common to all of said striker conductors, with a perforated strip controlling the passage of fluid through the supply conductor and acting to effect its operative connection with any selected one of the striker conductors. 70

24. In a machine of the class described, the combination of a plurality of strikers, and a fluid pressure apparatus for actuating the strikers, the said apparatus including a plurality of conductors one for each striker, a supply conductor, a channel or chamber 85 connecting the supply conductor with all the striker conductors, and valves shutting off communication between the connecting chamber and the striker conductors, with a perforated strip controlling the passage of fluid through the supply conductor and acting to open one of the valves to establish operative connection between the corresponding striker conductor and the supply conductor. 90

25. In a machine of the class described, the combination of a plurality of strikers, and a fluid pressure apparatus for actuating the strikers, said apparatus including a plurality of conductors connected to the respective strikers, a supply conductor, a channel or member connecting the supply conductor with all the striker conductors, valves for shutting off communication between the connecting channel and the 100 striker conductors, and further conductors connected to the several valves, with a perforated strip controlling the passage of fluid both through the supply conductor and a selected one of the valve conductors and thus to control the actuation of any selected one of the strikers. 105

26. In a machine of the class described, the combination of a series of strikers, and a fluid pressure apparatus for actuating the strikers, said apparatus including a set of conductors, one for each striker, and divided into a plurality of groups, a supply conductor for each such group, channels or chambers connecting each supply conductor with all the striker conductors of the corresponding group, and valves common to all of the connecting channels or chambers for shutting off communication between them and the several groups of striker conductors, 120 with a perforated strip controlling the passage of fluid through one of the connecting channels and acting to open one of the valves so as thus to establish communication between one of the supply conductors and one 125 130

- or another of the striker conductors of the corresponding group.
27. In a machine of the class described, the combination of a series of strikers, and a fluid pressure apparatus for actuating the strikers, said apparatus including a set of conductors, one for each striker, and divided into a plurality of groups, a supply conductor for each such group, channels or chambers connecting each supply conductor with all the striker conductors of the corresponding group, valves common to all of the connecting channels or chambers for shutting off communication between them and the several groups of striker conductors, and conductors connected to the several valves, with a perforated strip controlling the passage of fluid both through a selected one of the supply conductors and a selected one of the valve conductors so as thus to establish communication between said supply conductor and one or another of the striker conductors in the corresponding group.
28. In a machine of the class described, the combination of a plurality of strikers, and a fluid pressure apparatus for actuating the strikers, said apparatus including a plurality of conductors connected to the respective strikers, a supply conductor, a channel or chamber connecting the supply conductor with all the striker conductors, valves for shutting off communication between the connecting channel and the striker conductors, and further conductors connected to the several valves, with a perforated strip formed with two perforations, one controlling the passage of fluid through the supply conductor and the other the passage of fluid through the valve conductor, in the manner and for the purpose described.
29. In a machine of the class described, the combination of a series of strikers, and fluid pressure apparatus for actuating the strikers and including a series of conductors divided into a plurality of groups, and a perforated strip having a pair of perforations for each striker to be actuated, one acting to select one of the groups of conductors, and the other acting to select one or another of the conductors in such group.
30. In a machine of the class described, the combination of a series of strikers divided into groups, a perforated strip, and means controlled by the strip for actuating the strikers, the said strip being formed with a pair of perforations for each striker to be actuated, one acting to select one of the groups of strikers for actuation, and the other controlling the operation of the required striker in the selected group.
31. In a device of the class described, the combination of a series of strikers for actuating the key devices of a typographical or like machine, a further striker for actuating a periodically operated part of such machine, a perforated strip, and a fluid pressure apparatus controlled by said strip for effecting the actuating movements of all the strikers in the proper sequence.
32. In a device of the class described, the combination of a series of strikers for actuating the key devices of a typographical or like machine, a further striker for actuating a periodically operated part of such machine, a perforated strip, and means controlled by the perforated strip for effecting the actuating movements of all the strikers in the proper sequence.
33. In a typographical or like machine, the combination of a series of key devices, a perforated strip controlling the actuation of said devices, a periodically operated part of the machine, power driven mechanism for actuating said part, means controlled by the perforated strip for initiating the operation of the power-driven mechanism, and automatic means independent of the strip for arresting the operation of said mechanism when the periodically operated part has completed its cycle of operation.
34. In a typographical or like machine, the combination of a series of key devices, a perforated strip controlling the actuation of said devices, a periodically operated part of the machine, power-driven mechanism for actuating said part, fluid pressure means controlled by the perforated strip for initiating the operation of the power-driven mechanism, and automatic means independent of the strip for arresting the operation of said mechanism when the periodically operated part has completed its cycle of operation.
35. In a typographical or like machine, the combination of a series of key devices, a perforated strip controlling the actuation of said devices, a periodically operated part of the machine, power-driven mechanism for actuating said part, means controlled by the perforated strip for initiating the operation of the power-driven mechanism, automatic means independent of the strip for arresting the operation of said mechanism when the periodically operated part has completed its cycle of operation, and further means for arresting the operation of the power-driven mechanism upon the abnormal operation of the periodically operated part.
36. In a typographical or like machine, the combination of a series of key devices, a perforated strip controlling the actuation of said devices, a periodically-operated part of the machine, power-driven mechanism for actuating said part, means controlled by the perforated strip for initiating the operation of the power-driven mechanism, and automatic means independent of the strip for arresting the operation of said power-driven mechanism upon the abnormal operation of the periodically-operated part.

37. In a typographical or like machine, the combination of a series of key devices, a perforated strip controlling the actuation of said devices, a periodically-operated part of the machine, a constantly driven member normally connected to the perforated strip and normally disconnected from the periodically-operated part, means controlled by the perforated strip for effecting the operative connection of the driven member with the periodically operated part, and means for breaking the connection between the driven member and the periodically operated part when the latter has completed its cycle of operation without disturbing the connection between the driven member and the perforated strip. 70
38. In a typographical or like machine, the combination of a series of key devices, a perforated strip controlling the actuation of said devices, a periodically operated part of the machine, a constantly driven member normally connected to the perforated strip and normally disconnected from the periodically operated part, means controlled by the perforated strip for effecting the operative connection of the driven member with the periodically operated part, and means actuated by the abnormal operation of the periodically operated part for breaking its connection with the constantly driven member and also the connection between the constantly driven member and the perforated strip. 80
39. In a typographical or like machine, the combination of a series of key devices, a perforated strip controlling the actuation of said devices, a periodically operated part, a constantly driven member normally connected to the perforated strip and normally disconnected from the periodically operated part, means controlled by the perforated strip for connecting the constantly driven member to the periodically operated part, means acting automatically when the periodically operated part has completed its cycle of operation to break its connection with the constantly driven member without disturbing the connection of said member with the perforated strip, and further means acting automatically upon the abnormal operation of the periodically operated part for breaking the connection of the constantly driven member with both said part and the perforated strip. 90
40. In a linotype machine, the combination of a movable assembler elevator, power driven mechanism, means for effecting the operative connection of said mechanism to the elevator, and automatic means for breaking the operative connection between the power driven mechanism and the elevator when undue resistance is offered to the movement of the latter. 100
41. In a typographical or like machine, the combination of key devices, a perforated strip controlling the actuation of said devices, a periodically operated part, power-driven mechanism acting in the normal operation of said part for feeding the perforated strip, and means actuated upon the abnormal operation of said part for throwing the power-driven mechanism out of action. 110
42. In a linotype machine, the combination of key devices, a perforated strip controlling the actuation thereof, power-driven mechanism for feeding the strip, a line delivery carriage, and means actuated by the abnormal operation of the delivery carriage for throwing the power-driven mechanism out of action. 120
43. In a linotype machine, the combination of key devices, a perforated strip controlling the actuation thereof, power-driven mechanism adapted to be connected to and disconnected from the perforated strip, a line delivery carriage, and means to prevent the connection of the power-driven mechanism to the perforated strip except when the line delivery carriage is in its proper receiving position. 130
44. In a linotype machine, the combination of a movable assembler elevator, a delivery carriage to receive the line therefrom, power-driven mechanism for effecting the movement of the elevator, and means actuated by the abnormal operation of the line delivery carriage for arresting said power-driven mechanism. 140
45. In a linotype machine, the combination of a movable assembler elevator, power driven mechanism for effecting the movement thereof, a perforated strip for initiating the operation of said mechanism, and means actuated by the abnormal operation of the elevator for throwing said mechanism out of action. 150
46. In a linotype machine, the combination of a movable assembler elevator, a delivery carriage to receive the matrix line therefrom, power driven mechanism for effecting the movement of the elevator, a perforated strip for initiating the operation of said mechanism, and means actuated by the abnormal operation of the line delivery carriage for throwing said mechanism out of action. 160
47. In a linotype machine, the combination of a movable assembler elevator, power driven mechanism adapted to be operatively connected to said elevator and including devices movable relatively thereto when its movement is obstructed, and means actuated by the relative movement of said devices for throwing the power driven mechanism out of action. 170
48. In a linotype machine, the combination of a series of matrix releasing devices, a perforated strip, and a fluid pressure ap- 180

paratus controlled by said strip for actuating the matrix releasing devices individually and in proper sequence, the said apparatus including a set of conductors, one connected to each matrix releasing device, a second set of conductors of less number than that of the other set and coöperating with the strip, and automatic means acting selectively to establish communication between different

selected conductors of the two sets in effect- 10
ing the operation of the individual matrix
releasing devices.

In witness whereof I have hereunto set
my hand in the presence of two witnesses.

JACQUES MAYER.
